SEMI-AUTOMATIC PIVOT POLISHER

John E. Russell Markert, Lititz, and James Donald Smith, Lancaster, Pa., assignors to Hamilton Watch Company, Lancaster, Pa.

Application April 23, 1949, Serial No. 89,256

4 Claims. (Cl. 90—15)

1

This invention relates to an automatic pivot burnishing machine and is particularly directed to the adjustments of the machine by means of which either different size pivots may be accommodated or adjustments made to accommodate wear of the burnisher.

In the making of watches of the higher grade, everything is done that is possible to reduce friction. The degree of polish of the balance staff and the center and other pivots bears an important place in the friction developed in the running of the watch. The more friction the more power is dissipated and, therefore, the greater the size of the mainspring to make up for this dissipated power. Modern styles make it necessary for the watch manufacturer to use the smallest possible mainspring and the amount of power that can be saved or eliminated by overcoming frictional losses may mean the difference between a watch that sells and one which does not.

The object of the present invention is to provide a machine which passes through a single cycle of operation and stops, it being necessary to manually insert the workpiece and to manually start the machine for each workpiece.

It is a further object of the present invention to provide a machine which will consistently polish all pivots alike.

The present method of polishing is by hand and depends a great deal on the skill and experience of the operator. As skilled factory help is among the highest paid, any factor which eliminates the human skill is of great value to the industry.

It is a still further object of the present invention to remove the element of judgment from the operator in the use of a semi-automatic machine which having once been started on a cycle of operation continues and stops after completing the operation.

It is a still further object of the present invention to provide a semi-automatic machine which may be set up for pivots of different size through the means of adjusting screws and levers.

It is a still further object of the present invention to provide a semi-automatic machine which through adjustments produce a high quality bearing surface while at the same time hold a tolerance of $\frac{1}{10,000}$ of an inch in the finished product.

With the foregoing and other objects in view, the invention resides in the novel arrangement and combination of parts and in the details of construction hereinafter described and claimed, it

2 being understood that changes in the precise embodiment of the invention herein described may be made within the scope of what is claimed without departing from the spirit of the invention.

The invention is shown in the accompanying drawings in which:

Figure 1 is a perspective view looking from above the machine.

Figure 2 is a top plan view of a portion of the machine, omitting the driving means.

burnishing wheel and the pivot holder. Figure 4 is a greatly enlarged view of one type of pivot which is polished by the machine.

5. Figure 5 is a detail of the starting lever.
6. Figure 6 is a cross sectional view, with the burnishing wheel missing, of the pivoted frame which supports the burnishing wheel.

Figure 7 shows the locking mechanism for the starting lever and the cam for releasing said mechanism.

Figure 8 is a detail of the adjustable cam which controls the period of polishing.

Figure 9 is a plan of the workpiece in supported position.

Referring particularly to Figures 1 and 2, the machine is supported on a base 8 which has mounted at the rear thereof a partition 9 supporting two sets of bearings 10 and 11, in which is journaled a drive shaft 12. A slow speed motor 13 is connected through a gearing arrangement to a pulley 14 driving a belt 15 and a pulley

16 which is keyed to the shaft 12. A stepped pulley 17 is mounted on the shaft 18 and is connected to the drive shaft 12 through a cone clutch 19. Carried adjacent the bearing 10 is a cone brake 20 which is adapted to engage the stepped pulley 17 to afford controlled stopping of the drive shaft 12. Fixed on the shaft 21 is a second

of said pulley. Fixed on a shaft 21 is a second stepped pulley 22 which is connected to the first stepped pulley by a belt 23 and drives a gear 24 (see Figure 7) which is mounted in the gear housing 25. Meshing with the small gear 24 and also mounted within the gear housing 25 is a large gear 26 which rotates a shaft 27 carrying a cam 28. The gear box 25 and the shafts 21 and 27 are mounted in bearings carried in upstanding partitions.

The starting lever 29 (see Figures 1, 2 and 7) is pivotally mounted to the base at 30 and extends at one end into the gear housing 25 and at the other end extends toward the back of the machine where it is connected to a line 31 operated by a foot treadle (not shown). The depression of the foot treadle swings the lever 29

bringing the end 35 into engagement with the notch 38 of the latch 33. A spring 32 normally exerts an upward force on the backward extending end which is resisted by a latch 33 held in operating position by a spring 34 against the end 35 of the starting lever extending into the housing 25. Referring particularly to Figure 7 in which the mechanism is shown in operating position and just before the cam 28 engages the cam follower 36 of the latch 33 to release the starting lever 29 (which stops the cycle). At the instant of starting the mechanism, which will be hereinafter described, rotates the shaft 27 and the cam 28. A single rotation of shaft 27 (which is a complete cycle of operation) brings the cam 28 into engagement with the follower 36 releasing the latch 33 allowing the lever 29 to swing about the pivot 30 under the influence of the spring 32.

Referring to Figures 1 and 5, the movement of the foot treadle depresses the backward end of the starting lever causing the screw stud follower 39 and the clutch lever 40 to move at its downward end to the right, the screw stud following the slanting face 41 of the starting lever 29. The lever 40 which is pivoted at 42 moves the shaft 18 and its accompanying drum 43 into engagement with the cone clutch 19 and simultaneously out of engagement with the cone brake 20. This immediately causes rotation of the shaft 18 and its mounted pulley 17, the belt 23, the pulley 22 and the gearing 24 and 26 in the housing 25.

The shaft 27 which is journaled in the partitions 44 and 45 is turned through the gears 24 and 26 moving the cam 46 to permit the cam follower 47 to lower the arm 48 about the shaft 49 into the position shown in Figure 6, bringing the polishing wheel 50 into operation position.

The polishing wheel 50 performs three operations, that of cutting, polishing and burnishing. The cutting amounts to a removal of .0002 of an inch to .0008 of an inch. This cutting is very critical as the tolerance on these pieces is plus or minus .00005 of an inch. At the same time the wheel 50 cuts, it burnishes and polishes the surface both of the axis of the pivot and the shoulder which absorbs the thrust of the bearing. It is extremely important that the size be perfect and the finish be as highly polished as possible.

The arm 48 is pivoted on the shaft 49 and supports the shaft 51 in quill 52 which is mounted in the supports 53 and 54. A hand wheel 55 threaded on a pivoted stud 56 moves the upper support 53 about the pivot 57 to firmly hold the quill 52 against the lower support 54. This construction allows removal of the polishing head for refinishing of the polishing surface. A pin 54' is fixed in the support 54 to preposition burnisher 50 after sharpening and to align the oil hole 53' with an oil hole (not shown) in the quill of the burnisher 50.

The shaft 27 (see Figure 8) carries a cam 58 made up of a pair of plates 59 and 60 having slots 61 concentric with the shaft 27 to provide adjustment of the plates with relation to each other so that the cam surface 62 may be regulated. Set screws 63 hold the plates in adjusted desired position. A cam follower 64 carried on the end of a lever 65 is moved downward through the rotation of the shaft 27 and cam 58 and swings about the pivot 66 to move the bell crank 67 (see Figure 1).

The bell crank 67 is pivoted at 68 and provided at its upper extremity with a rounded end 69

engaging the collar 70 carried on the sleeve 71. Downward movement of the cam follower will move the sleeve 71 to the left (see Figure 1) bringing the cone clutch 72 into engagement and simultaneously releasing the cone brake 73. This action results in the simultaneous rotation of the pulleys 74 and 75. The rotation of the pulley 75 rotates pulleys 76 and 77 through the respective belts 78 and 79. The pulley 77 mounted on shaft 51 is the operating pulley for the burnishing head 50. The method of driving the pulley 77 through the pulleys 76 allows the burnishing head to rotate while the arm 48 is swung about the shaft 49 through the action of the cam 46 and its follower 47 so that the raising of the burnishing head from the work has no effect on the rotation of that head. Driven simultaneously with the pulley 75 is the pulley 74 which drives by means of a belt 80, a pulley 81. An idler pulley 82 is vertically movable in the standard 83 and regulates the tension in the belt 80 to insure against slippage of said belt.

The forward portion of the base 8 (see Figure 6) is grooved at 84 to receive the slide 85. The groove is provided with a movable gib 86, adjusted and held in position by the set screw 87. A stop 88 is located at one end of the slide and provided with a set screw 89 and a lock nut 90 to control the travel of the slide which positions the work face in relation to burnisher.

The slide 85 supports generally the mechanism for holding and rotating the workpiece and is moved in and out of position through the medium of a bent lever 91 (see Figures 1 and 2) which is pivoted at 92 to the base and rounded at one end as at 93 and provided at the other with a cam follower 94. The end 94 of the lever is acted upon by the raised portion 95 of the cam 96 moving the lever in a clockwise direction to push the slide against the action of springs 97 toward the left. A fine adjustment screw 98 prepositions the slide and its carried workpiece in relation to cam 96, which as will be hereinafter pointed out is extremely critical as between the workpiece and the burnishing head. Adjustably mounted on the slide and removable therewith is a base 99 (see Figure 3), held in adjusted position by means of slots 100 and nuts 101. Carried on the adjustable base 99 is a block 102 which has a vertical bearing slide 103 mounted thereon. This slide is adjustable for height by a microscrew 104 which very accurately regulates the vertical position of a shaft 105, which is securely held in the slide 103. A lock nut 106 securely holds the vertical slide bearing against the block 102 in the desired adjusted position but permits a longitudinal sliding movement of the shaft 105.

The end of the shaft 105 opposite the burnishing head is reduced to form an anchorage for a compression spring 107 which constantly urges the shaft toward the burnishing head bringing the adjustable stop 108 (shown on Figure 2) against the end of the lever 109. The compression spring 107 abuts against a shaft 110 which is mounted in a bearing 111 and has an adjustable nut 112 by means of which the pressure which forces the face 117 of the workpiece against the rim face 116 of the burnisher can be adjusted. The lever 109 which is pivoted at 113 is formed with a cam follower 114 for contact with the cam 115 to move the shaft 105 to the left, allowing work to drop out.

Rotatably carried on the end of the shaft 105 nearest the burnisher is the pulley 81. The shaft

105 is formed with an annular groove (see Figure 3) 118 which receives a screw pin 119 carried by the pulley to prevent longitudinal motion of the pulley on the shaft. In one face of the pulley and adjacent its periphery is fixed a pin 120 which projects outward from the pulley parallel to the shaft 105 and engages a driving element 121 carried on the adjustable cone bearing 122. The driving element has a hole formed adjacent its periphery to loosely receive the pin 120 by means of which the rotary motion of the pulley 81 is transmitted to the driving element which turns on the cone bearing 122. Located diametrically opposite the pin 120 is a turning finger 123 which is held fixed to the driving element by set screws 124 and is bent so that the free end will engage the workpiece to impart the rotary motion of the driving element 121 to the workpiece.

The workpiece, which is shown in Figure 4 about eighty times actual size, is the shaft for the third wheel of a watch and is formed with the integral pinion 125 and the pivots 126 and 127. Generally speaking an entire lot of staffs will be run through polishing the pivot 126 in one operation and on a second run polishing the pivot 127, the operating finger 123 being adjusted if necessary.

Shaft 105 is lapped to receive an inner removable spindle 128 which receives one pivot of the workpiece, the other pivot being laid in a notch 129 formed in the holding piece 129. The workpiece is then mounted for free rotation in the bearings 128 and 129 and turned entirely by contact of the finger 123 with the teeth of the pinion 125. This presents the true rotation that it would receive due to contact with gear teeth.

The slide 85 is in turn formed with a cross groove 130 in which is mounted a slide 131 which is adjusted by means of a microscrew 132. This accurately locates the transverse position of the plate 129 with respect to the spindle 128 of the shaft 105. Carried on the slide 131 is a support 133 to which is firmly screwed the plate 129. The support 133 is easily replaceable to accommodate different size pivots being positioned by steady pins (not shown) and held firmly by screws. The apron 135 deflects the workpiece into a pan 136 upon completion of the burnishing operation.

Serving as a limit stop for the burnishing wheel is a diamond knob 137 which is mounted on top of a threaded cylindrical rod 138 which is adjusted by means of a microscrew 139 and locked firmly in adjusted position by a set screw 140 passing through a hole 141 in the support 133. A peg 142 is carried on the slide 131 to support and hold in position the workpiece receiving tray 136.

In use a staff is taken from the tray 143 with the tweezers and inserted in the dead center 128 of the spindle 128 and laid in the groove in the piece 129 so that the finger 123 fits between the teeth of the pinion 125. The starting pedal (not shown) is then depressed by the foot pulling the starting lever 29 about the pivot 30 into the position shown in Figure 7 so that the end 35 is engaged by the latch 38 of the lever 33. Downward movement of the starting lever 29 (see Figure 5) causes the lever 40 to move the sleeve out of engagement with the brake 20 and into engagement with the clutch 19 causing rotation of the pulley 17 to be transmitted to the pulley 22 and the shaft 27.

Rotation of the shaft 27 moves the cam 46 out of engagement with the cam follower 47 allowing the arm 48 to slowly move about the pivot 49 and

bring the burnishing wheel 50 into contact with the surface 127 of the workpiece.

Continued rotation of the shaft 27 allows the cam follower 44 (Figures 1, 2 and 4) to drop off the raised surface of the cam 45 permitting the slide 85 through the action of the springs 97 to move and come to rest against the stop screw 89 which positions the workpiece so that the shoulder 117 is in contact with the edge 116 of the burnishing wheel. This is done previous to rotation of the burnishing wheel on the workpiece. This movement of the slide 85 by means of the springs 97 brings the face 117 of the workpiece against the rim face 116 of the burnisher, which forces the workpiece and its shaft carried spindle 128 toward the left against the spring 107. Thus the pressure between the face 117 of the workpiece and the face 116 of the burnisher is governed by the compression spring 107 which may be regulated by adjustment screw 112.

The continual turning of the shaft 27 (see Figure 8) rotates the cam 59 and moves the cam follower 64 of the lever 65 to release the shaft 71 from the cone brake 73 and into engagement with the cone clutch 72 which simultaneously rotates pulleys 74 and 75, thus starting rotation of the burnishing wheel and the workpiece at exactly the same time.

Rotation of the burnishing wheel is accomplished through the belt 78, pulley 76, belt 79 and pulley 77. The rotation of the workpiece is accomplished through the pulley 74 turning the pulley 81 through the belt 80 which passes over the idler pulley 82. Rotation of the pulley 81 on the shaft 105 is transmitted by the pin 120 to a driver element 121 and through the finger 123 to the workpiece. The diameter size of the pivot is controlled by an adjustable diamond knob 137 arresting the downward movement of the burnishing wheel.

Continued rotation of the shaft 27 allows the cam follower 64 to be engaged by the cam surface 62, cam 59 moving the shaft 71 out of engagement with the cone clutch 72, thus stopping rotation of the workpiece and the burnishing wheel at the same instant. The burnishing wheel now rests on the diamond knob 137 bearing but very slightly on the surface 127 of the pivot. The cams 115 and 95 contact the cam followers to move the levers 109 and 91 causing the shaft 105 to be withdrawn from the workpiece. The workpiece is now supported entirely by the weight of the burnishing wheel overlying the surface 127 of the pivot. The continued rotation of shaft 27 now brings the cam 46 into engagement with the cam 47, thus lifting the arm 48 and the attached burnishing wheel 50 into the position shown in Figure 3 at which time the staff will fall being deflected by the apron 135 into the tray 136. Further rotation of the shaft 27 brings the cam 37 into engagement with the follower 36 releasing the lever 29 from the notch 38 and moving the lever 40 against the inclined surface 41 to move the shaft 18 out of engagement with the cone clutch 19 and into engagement with the brake 20. The cycle is complete and the machine ready for reloading and another cycle.

The machine is provided with numerous adjustments by means of which it may be adapted to handle pivots of different sizes, that is within limits. The burnishing wheel must be removed periodically so that the carbide surface 116 and 144 may be refinished. This is done by using a diamond bonded grinding wheel to produce par-

allel cuts on the surfaces 144 and 116 to provide a cutting and polishing surface.

The plate 129 must be occasionally removed so that the groove in which the pivot rests may be lapped for accuracy or it may be replaced by one having a groove of different size. Micrometer screws 145 and 146 are provided in pairs to adjust the position of the burnishing head 50 about the pivots 147 and 148 respectively. Set screws are carried in all positions to lock the members after the desired adjustments have been made. The machine does rapidly and accurately a job which heretofore has been a specialized hand polishing job which required a great deal of time and skill. It is readily adaptable for different size work-pieces and they may be held to a tolerance of .0001 of an inch.

What is claimed is:

1. A semiautomatic pivot polishing machine comprising a base, a motor mounted on said base and serving as a source of power mechanism driven by said motor, manually operated means for starting a cycle of operation, mechanical means controlled through said operation for stopping said cycle of operation, means for mounting a staff between dead centers, a pivot polishing wheel adapted to be brought into contact with the pivot of the staff, means controlled in the cycle of operation for simultaneously starting rotation of the staff and the polishing wheel, means for simultaneously stopping said staff and polishing wheel and means for automatically discharging the staff upon the completion of the cycle of operation.

2. A semiautomatic pivot polishing machine comprising a base, a motor mounted on said base, a shaft continuously driven from said motor, pulleys mounted on said shaft, manually operated means for moving said pulleys into operative connection with said shaft, a cam rotated through said pulleys acting against said manually operated starting means to stop the rotation of said pulleys upon the completion of a single rotation of said cam, a workpiece, a polishing wheel adapted to be brought in contact with said workpiece, a second set of pulleys controlled through the operation of said first mentioned pulleys for simultaneously rotating the workpiece and the polishing wheel, means driven by said first mentioned pulleys for simultaneously stopping said workpiece and said polishing wheel whereby further movement of said first mentioned pulleys releases the workpiece from operative contact with said polishing wheel.

3. A semiautomatic pivot polishing machine comprising a base, a motor mounted on said base, a shaft mounted on said base and rotatably connected to said motor, pulleys carried on said shaft, means for operatively connecting said pulleys

with said shaft, means for stopping said pulleys during the continuous rotation of said shaft, means operated by one set of pulleys through a complete cycle of operation, an arm pivotally mounted on said base, means for adjusting said arm either longitudinally or laterally of said base, a polishing wheel carried by said arm, a slide mounted for lateral motion across said base, a pair of dead centers carried on said slide, microscopic adjustments for positioning said dead centers for supporting a workpiece to be engaged by said polishing wheel, means for simultaneously starting and stopping said workpiece and said polishing wheel and means for urging said workpiece against said polishing wheel.

4. A semiautomatic pivot polishing machine comprising a base, a motor mounted on said base, a shaft continuously driven by said motor also mounted on said base, pulleys carried on said shaft, means for operatively connecting and disconnecting said pulleys from said shaft, a slide mounted for lateral motion on said base, a shaft carried by said slide and movable longitudinally thereof, a pulley rotatably carried by said shaft, means connecting said first mentioned pulley to said last mentioned pulley, dead centers carried by said slide and in longitudinal line with said shaft for supporting a workpiece, means connected to said shaft mounted pulley for turning said workpiece, an arm pivoted to said base, a rotatable polishing wheel carried by said arm, means operated by said first mentioned pulleys for pivoting said arm to bring said polishing wheel into engagement with said workpiece, means for urging said workpiece against said polishing wheel and means for simultaneously starting and stopping said workpiece and said polishing wheel.
